UNITED STATES PATENT OFFICE.

WALTER C. BAKER, OF CLEVELAND, OHIO, ASSIGNOR TO THE AMERICAN BALL-BEARING COMPANY, OF SAME PLACE.

DESIGN FOR A YOKE FOR AUTOMOBILE STEERING-GEAR.

SPECIFICATION forming part of Design No. 33,646, dated December 4, 1900.

Application filed October 27, 1900. Serial No. 34,674. Term of patent 14 years.

To all whom it may concern:

Be it known that I, WALTER C. BAKER, a citizen of the United States, residing at Cleveland, in the county of Cuyahoga and State of Ohio, have invented and produced a certain new and original Design for a Yoke for Automobile Steering-Gear, of which the following is a specification, reference being had to the accompanying drawings, forming part thereof.

10 In the drawings, Figure I is a view in perspective of my new and original design for yokes. Fig. II is a longitudinal vertical section taken through Fig. I on line $x-x$. Fig. III is a transverse vertical sectional view taken on line $y-y$, Fig. I.

15 As illustrated by the drawings, it will be seen that the main features of the design are lightness, strength, and ornamentation.

A represents a shank. Connected to said shank A is a yoke-bar B, which is mounted

at one end of said shank and extends out from either side thereof. The yoke-bar B is formed with a depression or groove D, which is located between the ears or lugs C and C', which extend out from said bar and at approximately right angles therewith.

The essential feature of my design is the depressed or grooved yoke-bar B, with ears or lugs C and C' projecting at both ends.

What I claim is—

30 The design for a yoke for automobile steering-gear, substantially as shown and described.

Signed by me at Cleveland, Ohio, this 19th day of April, 1900.

WALTER C. BAKER.
